CLAIM

The ornamental design for a catheter securing device, as shown and described.

DESCRIPTION

FIG. 1 is a front, left, and top perspective view of a catheter securing device.

FIG. 2 is a back, right, and bottom perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a right elevation view thereof; and,

FIG. 8 is a left elevation view thereof.

The broken line portions show unclaimed subject matter only and form no part of the claimed design.
